UNITED STATES PATENT OFFICE.

JOHN G. KNURECK, OF WOODHAVEN, NEW YORK, ASSIGNOR TO UNDERWOOD TYPE-WRITER COMPANY, OF NEW YORK, N. Y., A CORPORATION OF DELAWARE.

TYPE-WRITING MACHINE.

1,260,209.

Specification of Letters Patent. Patented Mar. 19, 1918.

Application filed March 17, 1917. Serial No. 155,385.

To all whom it may concern:

Be it known that I, JOHN GEORGE KNURECK, a citizen of the United States, residing in Woodhaven, Long Island, in the county of 5 Queens and State of New York, have invented certain new and useful Improvements in Type-Writing Machines, of which the following is a specification.

My invention relates to typewriting machines, and is herein described as applied to an Underwood typewriting machine adapted to write flat stencil cards without noticeably bending them. It is customary to have such stencil cards made of a card- 10 board frame which is comparatively heavy, and having an opening across which is stretched a stencil sheet, said sheet being firmly attached to the cardboard. This sheet is usually moistened, preparatory to 15 cutting the stencil, to soften the material with which the sheet is coated, to enable the stencil to be written thereon. Any material bending of the cardboard frame is obviously disadvantageous if the card is to 20 be used in automatic addressing or similar machines, and further is likely to crack the stencil sheet in the opening or else may stretch it irregularly out of shape,—in any 25 event producing a poor effect when the stencil is used for addressing.

Since the stencil sheet included in said card is usually small, the writing of the typewriter covers only a very small part of the typewriter platen, thus rapidly marring 30 the surface of the platen,—this unfavorable action being especially increased by the fact that such stencil cards generally include several periods, with the result that the sharp period type of the typewriter soon seriously indents the platen. This injury to 35 the platen is the more serious in writing stencils with ordinary typewriter type, because the surface of the platen has to be much harder than an ordinary typewriter 40 platen if the stencil is to be satisfactorily cut, with the result that the rubber surface, instead of having the springiness inherent in ordinary correspondence typewriter platens, is so hard that the type tends 45 to permanently indent the platen before rebounding from it.

I have found it possible to avoid such difficulties by providing the platen with a re-

placeable hard surface in the form of a celluloid sheet, which not only will be harder 55 than the platen, but which also has the property of repelling water, thus materially improving the action of the type on a wet stencil sheet with the celluloid behind it. Such celluloid, however, is usually extremely 60 slippery, with the result that it does not get enough hold on the stencil card or sheet to cause the card and sheet to be fed forward satisfactorily. To overcome the difficulties arising from this slipperiness, I have found 65 it advantageous to construct the celluloid sheet and its holder so that the celluloid only covers part of the width of the card, while the card outside of the celluloid is gripped by an enlarged portion of the platen 70 which is extremely elastic, so that it tends to get a grip on the card sufficient to feed the card backwardly and forwardly. The celluloid strip need only cover the space occupied by the stencil sheet itself, so that if 75 the card-holder in which the stencil is mounted has other writing spaces on it, the types of the typewriter may write thereon, through the usual ribbon with the rubber of the platen serving as a backing in the usual 80 manner.

In order to provide for the writing of cards which are deeper than would be accommodated in an ordinary Underwood machine above the universal bar, said universal 85 bar may be made with U-shaped portions or goose-necks, thus providing an opening to accommodate a chute into which the stencil card feeds, the chute being for the purpose of holding the stencil card against the 90 platen and acting in lieu of the ordinary pressure rolls. The chute for this purpose may be provided with spring surfaces facing the platen, said surfaces adapted to press a card against the softer part of the 95 platen, and thereby increase the grip that the platen gets on the card.

To diminish the amount of slipping between the card and the platen, it will be found advantageous to connect flexible 100 bands to the platen and make the chute of such a shape that the flexible bands will lie against or be confined by the chute, and against which the face of the card bears. This makes the feeding of the card satisfactory. The ends of the bands may be

turned up so as to partly cover the opposite face of the card, thereby diminishing still further its friction in the chute.

Since these bands are preferably thin and 5 have not sufficient stiffness to force themselves down into the chute when the chute may be sticky from moisture which has run off, the platen is advantageously provided with a device for preventing its being rotated backward accidentally; said device, however, being releasable to permit the platen to be rotated backwardly if the operator puts a card in the chute and forces the bands down therein by pressure on the 15 top of the card.

Other features and advantages will hereinafter appear.

In the accompanying drawings,

Figure 1 is a sectional side view of an 20 Underwood typewriting machine, showing my invention as applied thereto.

Fig. 2 is a fragmentary skeleton perspective of part thereof.

Fig. 3 is a side view of a device for controlling the backward rotation of the platen.

Fig. 4 is a plan view of part of the platen on a larger scale, showing the celluloid sheet and its holder.

Fig. 5 is a sectional side view of the platen 25 and its chute at the moment of printing on an extension of the card.

Fig. 6 is a similar view, showing the movement of printing on the stencil part of the card.

Fig. 7 is a detail section of one end of the platen.

Fig. 8 is a front view of the stencil card-board-holder with a stencil thereon.

Type keys 1 when depressed carry down 10 key levers 2 to cause bell-cranks 3 to swing type-bars 4 upwardly and rearwardly, so that types 5 thereon strike against a front side of a platen 6. Said platen, as in the usual Underwood machine, is rotatably 15 mounted in a typewriter carriage 7, which slides on rails 8 and is drawn along to the left by means of a spring barrel (not shown), its movement being controlled by the usual rack bar 9 connected to the carriage, and meshing with the usual pinion 10 connected to the usual escapement wheel 11, on which the usual dogs 12 are alternatively effective. Said dogs are operated by the usual heels 13 on the type-bars 4, which 20 strike against a universal bar 14; said universal bar being mounted at its rear end on the usual rocker 15, and effective on the dogs 12 through the usual extension or lug 16, and being connected to said extension by deep U-shaped bars 17. The U-shaped bars 25 reach down almost to the key levers to permit a card 18, when inserted downwardly and inclined slightly rearwardly from in front of the platen, to drop without interference until it almost strikes said U-shaped

bars 17. At every operation of the universal bar, the usual ribbon holder or carrier 18^a is vibrated upwardly, so that a ribbon therein will print on the stencil card. For stenciling purposes, the ribbon is either 70 removed from the carrier 18^a or else the mechanism is provided with the usual silencing device for stencil cutting, shown in the Cook Patent, No. 926,050.

To vibrate the ribbon-carrier for printing purposes, the universal bar 14 is provided with the usual frame 19, comprising a slot 20, in which rides the usual pivot 21, said pivot being on one end of a U-shaped ribbon-vibrator 22, which is pivoted on the 80 frame at 23. In the present device, the vibrator 22 is U-shaped to match the bars 17, so that it will give the same clearance to the stencil card 18 that the bars 17 do. The present machine is shown without the 85 platen shift, so that it is only provided with a single set of types 5.

In order to hold the stencil card when it is projected downwardly into the bight of the U-shaped members 17 and 22, there is 90 provided a pair of channel bars 24, which form a chute to engage each margin of the stencil card 18. Each channel bar 24 is fastened to the typewriter carriage by means of a bracket 25, which is screwed to 95 the rear of its channel member 24, and is also fast to a bar 26^a, extending longitudinally of the typewriter carriage. The channel bars 24, each lap over the margin of the stencil card far enough to steady it, 100 and are set just far enough apart to permit the stencil card to slip down easily between them without binding, and yet to be closely guided. Each channel bar includes an opening 26 facing the other, and also includes a 105 front face 27, a back face 28, and a side face 29. Each channel bar extends considerably above the printing line and is closed at a bottom 30. The face 28, which is nearest the platen, is cut off at 31, Fig. 5, 110 low enough to clear the platen, its back face being at such a position that if it were projected, it would be tangent to, or slightly within, the surface of the platen, thus causing the stencil card to be guided against 115 the face of the platen. The outer face 27 of each channel bar 24, as stated above, projects above the printing line, but is cut away at the printing line to permit a flat spring 32 to press the stencil card against 120 the platen at that point, the spring being fastened to the face 27 by suitable screws 33.

The platen 6 is provided with the usual wooden center 34 and the rubber outer face 35. Since the effective printing length of 125 the platen, on which printing is done, is short, the remainder of the platen is cut away, so that the portions 36 of the typewriter axle between the part of the platen which is utilized and the ends of the type- 130

writer carriage are left open, thus reducing the weight of the carriage with the incidental reduction of noise, and so forth. The platen, however, is left long enough, so that 5 extensions of a rubber surface 37 on each side of the printing part of the platen are left intact. These extensions are provided with enlarged soft rubber rings for the purpose of engaging the margins of the stencil 10 card, as best illustrated in Fig. 7. In this figure is also shown a hub 38, by which the platen is supported on its axle 39.

In order to provide an effective hard backing surface for stencilizing a stencil 15 sheet 40, which is herein shown as at the bottom of the stencil card 18, and which is often wetted preparatory to writing, the platen is provided with a removable celluloid sheet 41. This sheet is thin enough to 20 be quite flexible and may be of any desired thickness, being advantageously about one thirty-second of an inch. This sheet is held in place by means of a pair of brass strips 42, which are held by screws 43 to the surface 25 of the platen and have each a slightly up-turned lip 44, adapted to catch the celluloid sheet, this lip extending longitudinally substantially the entire width of the celluloid sheet. Since the strip 42 is quite thin, 30 it usually need not be let into the platen, because whatever added thickness it gives to the platen where it lies on the surface thereof can usually be arranged to come just at the margins of the stencil sheet 40, with 35 the result that no writing will ever take place on the stencil sheet 18, where it overlies on either of the strips 42. The remainder of the platen, lying some distance outside of the stencil sheet 40, furnishes a 40 satisfactory writing surface. In order to insure contact of the stencil sheet 40 with the celluloid surface, so as to avoid breaking the sensitive surface of the stencil during the stencilization thereof, the upward 45 extensions of the faces 27 of the chutes 24 are curved rearwardly to a small extent, as seen at 45, in Figs. 5 and 6, thus slightly bending the stencil card at the printing point to insure close contact with the platen. 50 Inasmuch as the stencil card must move in the closely-fitting chute channel bars 24 with considerable friction, it is preferable to diminish said friction by, in effect, making one of the faces move with the platen. 55 To accomplish this, there is attached at each end of the platen (as by the end screws 43, Figs. 2 and 5) a strip 46, preferably a very thin ribbon of brass. Each strip or ribbon 46 is adapted to slide within its own channel 60 bar 24 and be co-extensive with the face against which it lies, or projecting only slightly beyond said face, as seen at 47, Fig. 2. Each strip 46 has a turned-up end 48, which catches over any card inserted and 65 thrust down into the chute, with the result that the platen is turned backwardly, because the end 48 enables the card to drag down its band 46. To prevent the platen from being thoughtlessly rotated backwardly, and thereby doubling up and injuring the bands 46, which may well be too flexible to feed backwardly into their channels, the usual line-space ratchet wheel 49 fast on the platen axle may be engaged by a spring-pressed pawl 50, which is adapted 70 to prevent backward rotation of the platen. In order to permit the insertion of a stencil card in the manner described above, the pawl 50 may be moved to ineffective position by means of a handle 51, (Fig. 3) which is 75 pivoted on the platen axle, and which includes a cam 52, which is adapted to be effective on a pin 53 fast on the pawl 50, so as to shift said pawl to idle position when the handle is drawn upward. Therefore to 80 insert a card, it is thrust downwardly as far as desired into the channel bars 24, and, after having been inserted, it may be fed forwardly or upwardly in the usual manner by the operation of a line-space handle 54, 85 which is effective to variably rotate the platen through the usual pawl 55. It will be noted that the bands 46 overlie the soft extensions 37 of the platen, but, since they are very thin, they do not add enough to 90 the diameter thereof to interfere with the proper feeding forward by the platen. 95

The celluloid strip 41, in usual writing, will write two or three hundred stencil cards, and then will usually be found marred 100 enough by the writing to make it advisable to replace it with a new piece of celluloid. In order to keep the flexible bands 46 within their proper channel bars 24, they may be provided with a guide in the form of a spacing bar 55, which engages them both. In order to prevent the platen from being rotated backwardly far enough to bend the bands 46 backwardly over the strip 42, by 105 which they are held, and thus breaking them 110 by the sharp bend induced thereby, the backward rotation of the platen may be limited by a stop 56, formed on a disk 57 connected to the right-hand end of the platen axle and engaging a pin 58 fast in the platen frame. 115 In order to limit the forward rotation of the platen, there may be provided a second disk 59, which is fast to the platen axle, and which comprises a stop 60, also adapted to strike the pin 58, and thereby limit the rotation of the platen in the opposite direction. 120 For the purpose of adjusting these disks relatively to each other, there is provided a screw 61, passing through a slot 62 in the disk 59, said screw engaging the disk 57, 125 with the result that by releasing the screw 61, the disk 57 may be released from the platen shaft and its stop 56 shifted to a new position. This enables the operative to insert stencil cards into the machine and to 130

take them out at the right line-space, without paying particular attention to them, because, on the one hand, the stencil card, when inserted, rotates the platen until it is brought 5 to rest by the stop 56, and, on the other hand, the stencil card is to be taken out of the machine when it is no longer possible to operate the line-space mechanism, because the stop 60 prevents further rotation of the 10 platen.

Variations may be resorted to within the scope of the invention, and portions of the improvements may be used without others.

Having thus described my invention, I 15 claim:

1. In a typewriting machine, the combination with a card-holding device, of stops for limiting the rotation of the platen, a removable hard face forming part of the 20 platen, a rubber face forming the remainder of the writing surface of the platen, and rubber margins for said platen projecting above the surface of said hard face to grip a card to feed it around the platen.

2. In a typewriting machine, the combination with a revoluble platen, of a straight card-guiding chute mounted at the front of the platen below the printing line, to hold a substantially flat card in printing position 30 against said platen, card-guiding fingers extending upwardly from said chute above the printing line adapted to slightly curve the card to the platen at the printing point, and means sliding within the chute to engage 35 the card by its lower edge, to slide the card upwardly relatively to the chute.

3. In a typewriting machine, the combination with a revoluble platen, of a chute adjacent said platen for guiding a card to 40 printing position, a spring at each side of the chute adapted to press the card at the printing line against the platen, and an enlarged soft gripping surface on each end of the platen, adapted to engage margins of 45 the card to permit the card to be firmly gripped by the platen where pressed against it by said spring.

4. In a typewriting machine, the combination with a revoluble platen, of a chute 50 adjacent said platen for guiding a card to printing position, a spring at each side of the chute adapted to press the card at the printing line against the platen, an enlarged soft gripping surface on each end of the 55 platen, adapted to engage margins of the card to permit the card to be firmly gripped by the platen where pressed against it by said spring, and bands lying within said chute attached to the platen adapted to frictionally engage the card to slide it relatively to the chute.

5. In a typewriting machine, the combination with a revoluble platen having a rubber surface, of a detachable celluloid piece 65 forming part of the surface of said platen

overlying the rubber, and a soft rubber enlarged section on each end of said platen for gripping a card where it lies upon the celluloid on the printing line.

6. In a typewriting machine, the combination with a revoluble platen having a rubber surface, of a detachable celluloid piece forming part of the surface of said platen overlying the rubber, a soft rubber enlarged section on each end of said platen for gripping a card where it lies upon the celluloid on the printing line, stops for positioning said platen, and a chute for guiding a card to said platen and comprising a member adapted to position the card with reference 80 to said celluloid.

7. In a typewriting machine, the combination with a revoluble platen and a chute adjacent thereto for holding a card, of an extension on said chute adapted to slightly 85 curve a card back against said platen and situated above the printing line, and springs forming part of said chute to press a card against the platen at the printing line.

8. In a typewriting machine, the combination with a revoluble platen and a chute for holding a card adjacent thereto, of extension fingers on said chute adapted to slightly curve a card back against said platen and situated above the printing line, 90 springs forming part of said chute to press a card against the platen at the printing line, and bands within said chute attached to said platen and forming part of one face of said chute adapted to slide the card relatively to said chute past said springs and 95 fingers.

9. In a typewriting machine, the combination with a revoluble platen and a chute for holding a card adjacent thereto, of extension fingers on said chute adapted to slightly curve a card back against said platen and situated above the printing line, 100 springs forming part of said chute to press a card against the platen at the printing line, bands within said chute attached to said platen and forming part of one face of said chute adapted to slide the card relatively to said chute past said springs and 105 fingers, and means for preventing accidental 110 backward rotation of the platen to prevent doubling of the bands in said chute.

10. In a typewriting machine, the combination with a revoluble platen and a chute for holding a card adjacent thereto, of extension fingers on said chute adapted to slightly curve back a card against said platen and situated above the printing line, 115 springs forming part of said chute to press a card against the platen at the printing line, bands within said chute attached to said platen and forming part of one face of said chute adapted to slide the card relatively to said chute past said springs and 120 fingers, means for preventing accidental 125 backward rotation of the platen to prevent doubling of the bands in said chute.

130

- backward rotation of the platen to prevent doubling of the bands in said chute, and a stop for limiting the rotation of said platen to a point where said bands will be damaged by being bent by said platen. 5
11. In a typewriting machine, the combination with a traveling carriage, of a chute fast on said carriage comprising two channel members terminating adjacent the printing line, extensions to said channel members to slightly bend the card against the platen at the printing line, and springs adjacent the printing line for holding the card against the platen. 10
12. In a typewriting machine, the combination with a traveling carriage, of a chute fast on said carriage comprising two channel members terminating adjacent the printing line, extensions to said channel members to slightly bend the card against the platen at the printing line, springs adjacent the printing line for holding the card against the platen, and bands attached to said platen lying within said chute adapted to feed a card relatively to said chute past the printing line. 15
13. In a typewriting machine, the combination with a traveling carriage, of a chute fast on said carriage comprising two channel members terminating adjacent the printing line, extensions to said channel members to slightly bend the card against the platen at the printing line, springs adjacent the printing line for holding the card against the platen, bands attached to said platen lying within said chute adapted to feed a card relatively to said chute past the printing line, and a stop for preventing a revolution of said platen to a point where the platen will bend the bands to injure them in the chute. 20
14. In a typewriting machine, the combination with a revoluble platen, of a guide in front thereof and below the printing line, for holding and advancing cards adjacent said platen, said guide comprising a movable device connected to said platen and forming one side of the face of said guide, and having means to engage the bottom edge of the card, for raising the latter relatively to the remainder of said guide. 25
15. In a typewriting machine, the combination with a revoluble platen, of a card-guiding chute adjacent said platen and in front thereof and arranged below the printing line thereon, and having inner and outer coöperative faces and adapted to hold the card against the platen, and bands connected to the platen, the bands lying against the inner face of the chute for engagement with the card therein, and having means to engage the lower edge of the card to advance it up out of the chute. 30
16. In a typewriting machine, the combination with a revoluble platen and a card-guiding chute adjacent thereto to co-act therewith, said chute extending below the printing line in front of the platen, of flexible work-carrying bands extending into said chute comprising devices adapted to engage by its lower edge a card inserted in said chute, and a device normally preventing backward rotation of the platen, to prevent accidental doubling of the bands in the chute. 35
17. In a typewriting machine, the combination with a revoluble platen, of a card-guiding chute in front thereof and arranged below the printing line, to receive a card to be stenciled and written upon, and having means at its upper portion to press a substantially straight card against the platen, means lying within the chute and connected to the platen and engageable by the bottom of the card inserted in the chute, to revolve the platen backwardly, and a stop for arresting the backwardly-rotating platen when the card has reached the necessary position for writing the first line thereon. 40

JOHN G. KNURCK.
